(57) **CLAIM**

The ornamental design for a gaming machine with movable display, as shown and described.

DESCRIPTION

FIG. 1 is a front perspective view of a gaming machine with movable display showing our new design in a first state; FIG. 2 is a front view thereof;

FIG. 3 is a left side view thereof;

FIG. 4 is a right side view thereof;

FIG. 5 is a top view thereof;

FIG. 6 is a front perspective view of a gaming machine with movable display showing our new design in a second state; FIG. 7 is a front view thereof;

FIG. 8 is a left side view thereof;

FIG. 9 is a right side view thereof; and,

FIG. 10 is a top view thereof.

The broken lines depicting the remainder of the gaming machine show features that form no part of the claimed design.

1 Claim, 10 Drawing Sheets
